UNITED STATES PATENT OFFICE.

CHARLES L. PAULUS AND ROBERT KAUCH, OF DAYTON, OHIO.

FLARE BRACKET.

Application filed October 9, 1923. Serial No. 667,512.

This invention relates to an improved flare bracket for carrying flare candles on the tips of the wings of an airplane or on other parts for night flying.

The principal object of the invention is to provide a device of this kind wherein provision is made for mounting a flare candle in an approximately horizontal position with its lit end to the rear; for suitably adjusting the flare candle relative to its bracket as necessitated by the different positions in which the bracket has to be fastened for different installations, and where it is desired to tilt the candle slightly with its shield so that illumination ahead may be secured; for so mounting and shielding the flare candle to eliminate the hazard of fire; and for adjusting the shield or guard to protect the pilot from the glare of the burning candle and to properly reflect the light of the candle.

The foregoing and other minor objects of the invention are set forth in the following detailed description, wherein reference is made to the accompanying drawings, in which:—

Fig. 1 is a perspective view of the end of an aerofoil showing the flare bracket of our invention mounted thereon.

Fig. 2 is a plan view of the bracket removed from the aerofoil.

Fig. 3 is a front view thereof, and

Fig. 4 is a central vertical longitudinal section.

Throughout the views, the same reference numerals are applied to the same parts.

The flare bracket may be mounted in any one of a number of places but is ordinarily carried on the under side near the tip of the wing and adjacent the outer extremity as shown in Fig. 1. The structure is carried by a support 10 suitably bolted adjacent a rib of the aerofoil 11, and in such close proximity with the skid 12 as to avoid contact with the ground in case the airplane rocks sidewise in landing, or taking off. The bracket proper is indicated at 13 and is suitably of sheet metal construction with a streamline contour to minimize head resistance. The bracket is pivoted at 14 to the support 10 to swing on a horizontal axis parallel with the leading edge of the wing to secure the proper positioning of the flare candle carried thereby regardless of the angle of incidence of the supporting surface on which the bracket is carried, the

purpose being ordinarily to have the flare candle in approximately horizontal position. In some instances the candle is tilted with its bracket to secure illumination ahead. As it most clearly appears in Fig. 4, the support 10 has depending wings 15 in which are provided circumferentially arranged openings 16 into any one of which a stud 17 on the free end of a leaf spring 18 is arranged to project. The springs 18, of which there are two, one on each side of the bracket 13, are suitably secured at their inner ends by the rivets 14 constituting the pivotal connection between the support 10 and the bracket 14. To adjust the bracket, it is necessary only to disengage the studs 17 by spreading the leaf springs 18 which can be done by hand since the outer ends of the springs are turned out to provide finger pieces 19. The bracket 13 has a flare candle holder 20 in which the flare candle is rigidly held upon compression of the jaws 21 by turning the wing nut 22. The holder is provided with direct electrical connection at 23 and 24 by wires 25 and 26 extending along the wings to the cockpit where the pilot has a switch for controlling the connection of the flare candles with a battery.

A trough-shaped sheet metal shield or guard 27 is provided for the flare candle to avoid the danger of fire and in a measure to cast the light of the candles downwardly but mostly to avoid a glare which would blind the pilot and render the use of the candles dangerous. These guards are entered between guides 28 in the forward portion of the bracket 13 and suitably secured by a bolt 29 at the rearward end of the bracket. Adjustment of the guard about its longitudinal axis is afforded through the provision of three or more openings 30 in the guard through any one of which the bolt 29 may be passed. In this way, in the use of the flare bracket on different types of planes, the proper adjustment of the guard will eliminate fire hazards and also avoid a glare being communicated to the pilot from the burning candles. It is apparent that in any position of forward and back adjustment of the flare bracket, necessary in bringing the flare candle to approximately horizontal position, because of the angle of incidence of the wing or inclination of the part on which the bracket is mounted, the lateral adjustment of the guard will effectually prevent the communi-

cation of a glare and at the same time eliminate the fire hazard. The guards are particularly useful on monoplanes where the pilot is ordinarily in a position with the flares in a direct line of vision.

The mounting of the flares horizontally, or substantially so, with the lit ends rearward has been found to be advantageous and to result in the flares burning more evenly and lasting longer. This is due to the fact that when so positioned they are disposed with their axis in the line of the slipstream and the lit ends are not subject to any impinging action of the slipstream as they are in cases where the flares are vertically arranged for example. The impinging action in the latter case caused burning particles to break off and the flares to burn unevenly and much faster than in the case where the flares are disposed relative to the slipstream as herein shown. The fire hazard introduced by burning particles being blown off is of course eliminated in this case where the slipstream has no direct impinging action on the burning ends of the flares.

We claim:

1. In a flare bracket, a flare holder for supporting flare candles in a substantially horizontal position, and a horizontal guard for partially enclosing said flare adjustable relative to said holder about the axis of the flare held therein.

2. In a flare bracket the combination of a holder for a flare candle supporting the same with the length thereof fore and aft in the propeller slipstream of an aircraft, and a flare guard of a substantially trough-shape adjustably mounted on said bracket for lateral adjustment relative to the flare.

3. In an aircraft flare bracket, a bracket and a glare guard, means associating the aircraft and bracket, whereby the bracket may be fixed in any predetermined plane about a horizontal axis and said glare guard being adapted to be adjusted about a transverse axis.

4. In a flare bracket for aircraft, the combination of a substantially trough-shaped

sheet metal flare guard arranged substantially horizontal and longitudinally in the slipstream of the aircraft propeller, a flare holder for supporting a flare candle beneath said guard and substantially parallel with respect thereto and means associating the aircraft and flare guard and holder, whereby they may be fixed in any predetermined plane about a horizontal axis.

5. In a flare bracket for aircraft, the combination of a substantially trough-shaped sheet metal flare guard arranged substantially horizontal and longitudinally in the slipstream of the aircraft propeller, a flare holder for supporting a flare candle beneath said guard and substantially parallel with respect thereto, and means for supporting said guard for adjustment about its longitudinal axis.

6. In a flare bracket for aircraft, the combination of a substantially trough-shaped sheet metal flare guard arranged substantially horizontal and longitudinally in the slipstream of the aircraft propeller, a flare holder for supporting a flare candle beneath said guard and substantially parallel with respect thereto, and means for supporting said guard for adjustment about its longitudinal axis.

7. In a flare bracket for aircraft, a support, a bracket of a slipstream form pivotally mounted on said support, a flare holder at the outer end of said bracket for supporting a flare candle substantially horizontal in the slipstream of the aircraft propeller, a sheet metal guard for the flare candle arranged edgewise in the slipstream substantially enclosing the flare candle and having lateral reflecting portions for reflecting the light of the candle, and means for adjustably mounting said guard on said bracket about the flare candle.

In testimony whereof, we affix our signatures.

CHARLES L. PAULUS.
ROBERT KAUCH.
